UNITED STATES PATENT OFFICE.

GEORGE WHITE, OF JERSEY CITY, NEW JERSEY.

IMPACT-ENGINE.

SPECIFICATION forming part of Letters Patent No. 683,537, dated October 1, 1901.

Application filed September 21, 1897. Renewed August 29, 1901. Serial No. 73,702. (No model.)

To all whom it may concern:

Be it known that I, GEORGE WHITE, a citizen of the United States, residing in Jersey City, in the county of Hudson and State of New Jersey, have invented a certain new and useful Improvement in Impact-Engines, of which the following is a specification.

In those engines which are driven by the energy of impact of fluids in motion the maximum efficiency of conversion is obtained by a total arrest of the motion of the driving fluid. In practice, however, a certain amount of residual velocity must be allowed for in order that the working fluid may be got out of the way after it has done its work. In order that the maximum work effect may be produced in the face of this last-named condition, the surfaces of impact in the engine should be arranged to finally discharge the working fluid in a direction parallel and directly opposed to the direction of movement of said surfaces of impact and the working fluid should be delivered to the engine from its proper jet-tube as nearly in the line of movement of the said surfaces as possible.

It is the main object of my invention to supply a construction wherein these conditions of maximum efficiency may be present.

My invention also comprises a number of details of construction hereinafter described and claimed.

In the accompanying drawings, Figure 1 is a sectional view of the working parts of a turbine, preferably for use with steam, a portion of the working wheel and a number of the jet-tubes and tube-holders being removed. Fig. 2 is an elemental form of bucket embodying the essentials of my invention. Fig. 3 is a side view of a portion of a working wheel or disk, showing the preferred arrangement of the form of bucket shown in Fig. 2. Fig. 4 is a view similar to Fig. 3 illustrating the use of an improved and preferred form of bucket embodying the essential characteristics of the form shown in Fig. 2. Fig. 5 is a face view of said preferred form of bucket. Fig. 6 is a perspective view of the same, and Fig. 7 is a sectional view of a preferred arrangement of jet-tube and tube-holder.

My invention is very simply embodied in the form of bucket shown in Fig. 2, wherein

the tube 1 is the directing portion and the curved surface 2 the reversing portion of my bucket. In one aspect and considered simply as applied to a bucket however mounted on a wheel these two portions are essentials of my invention. I prefer to mount the tube on a base 3, which is best continued in one piece into the reversing-surface 2. Any method of fastening the properly-shaped reversing-surface to the base would be within the present invention, however.

As shown most plainly in Figs. 2 and 6, the surface 2 is curved, so that its extreme lip 4 is parallel to the base 3. This lip is the point of discharge of the working fluid after it has done its work. The shape of the reversing portion 2 is such, therefore, that any fluid that is projected through the tube 1 will be turned through one hundred and eighty degrees of arc and will leave the bucket in a direction the reverse of that which it has in said tube. This form of bucket may be used in many well-known ways on a turbine or impact wheel without departing from my invention so long as the fluid is arranged to be projected by the agency of the directing-surface of the bucket into the reversing portion thereof.

In my preferred form of turbine the buckets are mounted upon a disk in a manner fully revealed by Figs. 3 and 4. The relation of the buckets to the driving fluid is shown by the outlines 5 in Figs. 3 and 4, which indicate the jet-tubes from which the water, steam, or other fluid is discharged. This is more fully shown in Fig. 1 in relation to the use of the buckets on both sides of the work wheel or disk, which is the construction preferred.

It will be seen from Fig. 3 that the working fluid will pass into the tubes 1 of successive buckets in turn and will be discharged from the lips 4 over said tube. During the time occupied by any one bucket in passing through the path of delivery of the working fluid the axis of the curved surface of impact or reversing portion of the bucket will change its angle with relation to the direction of fluid movement as it leaves the jet-tube 5; but since the fluid is at all times received by the directing-tube 1 it will always be given

such a direction as to fall against the curved surface 2 at right angles to its axis, and thus insure complete reversal of movement irrespective of the angle made at any given instant with the direction of the jet. The deflection of the fluid by the tubes 1 will work no detriment, since it is accomplished by a conversion of energy taken up by the working disk on which the bucket is mounted.

10 I have found that a cheaper and better construction embodying my invention as applied to the bucket proper is that shown in Figs. 5 and 6. Here the tube 1 is replaced by a sluice-way formed upon the base 3 by the sides 7 and 8. I have found that in practice the fluid as it strikes the base 3 flattens out and forms a layer easily confined and directed by the sides 7 and 8. Thus the function of the tube 1 is accomplished without the use of the 15 covering portion over the stream of fluid. In order, however, to best accomplish this flattening out of the stream and consequent directing action, it is desirable that the direction of the entering fluid should have a small 20 component at right angles to the plane of the work-wheel. For this purpose I have made my engine with converging jet-pipes, which throw the fluid at an angle to the plane of the work-wheel instead of parallel thereto, as has 25 been done heretofore in connection with forms of buckets approaching mine in appearance.

I prefer to use my improved buckets as shown at 9 in Fig. 4, although they may be given various shapes and be variously mounted upon the working wheel without departing from my invention.

As shown in Fig. 4, the buckets are set at a small angle to the circumference and, as shown in Fig. 5 at the point 6, the outer 30 edge of each bucket preferably conforms to the arc of the work-disk. Successive buckets are made to overlap, as shown, and it is for this reason that the side 8 is made shorter than the side 7. The outer points of these 35 sides coincide and are so placed as just to clear the jet-tube 5. It will be understood that the ends of my invention will be just as fully carried out if the overlapping sides are not made double, as shown, and if the longer 40 side of one bucket also serves as the shorter side of the next.

The working parts of my preferred engine are shown in Fig. 1, wherein it is made clear that the improved buckets shown in Figs. 5 and 6 are mounted upon both sides of a driving-disk 10, mounted in any well-known way to permit of the utilization of power. It will of course be understood that the buckets on one side must necessarily differ in shape from 55 those on the other side so far as the direction of the lateral curvature of the base 3 is concerned.

In order to avoid interference of the exhaust fluid with the fluid entering the bucket 60 behind it, there should be no confining agent on the exhaust side of the buckets. When a free space is left around the wheel, as in my

construction, the steam on leaving the bucket is found to take a direction somewhat away from the plane of the wheel, said direction 70 being the resultant of that portion of the driving fluid which has passed around in contact with the full curve of the reversing-surface and of another portion which piles up within the bucket, owing to the greater speed 75 of the fluid than of the wheel, and which tends to escape at right angles to the wheel. In order that this piled-up fluid, which does not pass around in contact with the reversing-surface, may be a minimum and may at 80 the same time be free to exert its influence in throwing the exhaust fluid away from the wheel, my bucket is made with a reversing-surface, which incloses a clear space within its 85 semicylinder, as opposed to those buckets wherein a diaphragm or partition is made to project into the space inclosed by the semicylinder. Such a partition tends both to increase the proportion of fluid which piles up or crowds within the bucket and to throw the exhaust 90 fluid back into the sphere of the driving fluid of the following bucket.

In my preferred construction the jet-tubes 5 are supported by holders 11 and preferably contain needles 12, which may be screwed 95 into the holders, as at 13. These needles pass through apertures 14 in the hollow bolts 15, (see Fig. 7,) upon which bolts the holders 11 are fastened by any means—as, for instance, nuts 16.

Concentric with the hub 17 of the disk 10 (see Fig. 1) is a fluid-chamber 18, to which the fluid is admitted by the pipe 19. At intervals upon the chamber 18 are set the bolts 15, which carry the holders and jet-tubes and 105 communicate directly with the fluid-chamber 18, as at 20. The openings 14 admit the steam or other fluid from the hollow bolts to the jet-tubes.

Any number of holders, with their jet tube 110 or tubes, may be used without departure from my invention; but I prefer to use these holders symmetrically in pairs around the wheel to balance the effort.

The construction of fluid-chamber and jet-tubes and holders shown and described herein produces in an engine of this kind the maximum simplicity and permits the speediest and easiest construction in the first instance and repairs during running of the machine. 115 120

Many details of my invention may be greatly modified and certain parts changed in their relations to others without departure from my invention.

125 What I claim is—

1. In an impact-engine, a work-disk, and buckets fastened on the side thereof, said buckets each comprising a directing-surface parallel to the plane of said disk, and a reversing-surface, forming a continuation of said directing-surface and turned away from said disk; in combination with jet-tubes inclined at a small angle to the plane of said

- wheel so as to flatten the driving fluid upon said directing-surface.
2. In an impact-engine, a work-disk, and buckets fastened on the side thereof, said 5 buckets each comprising a reversing-surface turned away from said disk, and a flat base and confining sides parallel to the plane of said disk, and so arranged as to direct the entering fluid first on said flat base and 10 always at right angles to the axis of curvature of said reversing-surface.
3. In an impact-engine, a work-disk, buckets fastened on the side thereof, and a free 15 space at the sides of said disk and buckets for receiving the exhaust fluid, each of said buckets comprising a directing-surface and a reversing-surface forming a continuation thereof; in combination with jet-tubes inclined at a small angle to the plane of said 20 wheel so as to flatten the driving fluid upon said directing-surface.
4. In an impact-engine, a plurality of buckets for receiving the driving fluid, each bucket comprising a flat directing-surface, confining 25 sides bordering the same, and a reversing-surface; said buckets being overlapped so that one of said confining sides forms a sharp edge for splitting the stream of fluid.
5. In an impact-engine a plurality of buckets 30 for receiving the driving fluid, each bucket comprising a flat directing-surface, confining sides bordering the same, and a reversing-surface; said buckets being overlapped with the long confining side of one in contact with
- the short confining side of the next, to form 35 a sharp edge for splitting the stream of fluid.
6. In an impact-engine, a work-disk, a jet-tube holder having apertures converging upon opposite faces of said disk, and jet-tubes fitted into said apertures, substantially 40 as described.
7. In an impact-engine, a work-disk, a hollow jet-tube holder having apertures converging upon opposite faces of said disk on the delivery side thereof, and corresponding converging apertures on the opposite side thereof; in combination with jet-tubes fitted into said 45 first-named apertures, and directing-needles fitted into said latter apertures, so that said needles enter said jet-tubes from within said 50 holder.
8. In an impact-engine, a bucket having a directing-surface for receiving the first impact of the driving fluid and a semicylindrical reversing-surface forming a continuation of 55 said directing-surface and inclosing a clear space within its semicylinder, whereby the accumulated fluid is enabled to produce an exhaust away from the plane of the directing-surface; all in combination with a jet-tube 60 arranged to project the driving fluid at a small angle directly upon the directing-surface.

GEORGE WHITE.
